GUSTAVE LYON, OF PARIS, FRANCE.

APPARATUS FOR TREATING WOOD WITH OZONE.

Application filed January 16, 1923, Serial No. 613,068, and in France January 27, 1922.

The present invention relates to apparatus specially designed for effecting the drying and seasoning of wood with ozone.

The course to be followed in this process 5 consists in subjecting pieces of wood or the like material in a closed vessel called "cell" to successive treatments recalling natural processes, and varying according to the characteristic and nature of the material to be 10 seasoned, but arranged according to a well defined time cycle and recurring automatically. Two methods of application will be described, in one of which the work is done at a pressure slightly lower than that of the 15 atmosphere, and in the other at a pressure slightly higher.

For the better comprehension of the arrangements adopted in the apparatus, it may be of use to give by way of example a schedule of the treatments to be followed in a given case; the data, which may vary, are naturally the times allowed for each treatment. This case corresponds with that in which the work is carried on slightly below 25 atmospheric pressure.

	Seconds.
1st. The air contained in the cell, charged with moisture, is replaced by dry air.	90
Time occupied	90
2nd. Exhaustion of the closed cell by about 1/20th of an atmosphere. Time occupied	30
3rd. Ozonization and circulation of the exhausted air in the cell. Time occupied	150
4th. Admission slowly into the cell of dry ozonized air until atmospheric pressure is restored. Time occupied	70
5th. Ozonization and circulation of the air inside the cell at atmospheric pressure. Time occupied	50
6th. Standing. Time occupied	210
 Total of cycle	 600
45 The apparatus, which forms the subject of this invention allows of the several operations enumerated above being carried out automatically and being repeated automatically for the necessary length of time.	
50 The aggregate of the apparatus is controlled by a special clock which opens or closes at definite times the electric circuits governing the several elements included in a complete plant.	

In the accompanying drawings 55 Fig. 1 is a diagram of a complete plant according to the invention.

Figs. 2 and 3 illustrate the controlling clock.

Figs. 4, 5 and 6 are several views of a valve 60 with automatic electro-pneumatic opening.

Fig. 7 is a diagram of an alternative arrangement.

Referring to the diagram, Fig. 1, 1 is the control clock to be described subsequently, 65 2 is the cell, 3 is the source of dry air, 5 is the ozonizer, 18, 19, 20, 21, 22, 23 and 24 are different servo-motors to which are coupled the electromagnets for opening and closing, the various pipes include the main exhaust pipe 6, the main dry air supply pipes 4 and 16, the pipe 15 connecting the source of dry air with the servo-motor 21 for supplying the ozonizer with dry air.

As shown the following servo-motors are 75 connected to the main exhaust pipe, viz., 19, 20, 21, 22 and 23, also the ozonizer 5 is connected at its inlet through the pipes 13 and 14 to the servo-motors 21 and 22, the outlet of the ozonizer 5 is connected to the servo-motor 19 by a pipe 12.

The pipes connected with the cell 2 includes the pipes 10, 7, 4, 8 and 9; and finally 80 a pipe 11 connected with the exhaust pipe 6 is a part of the servo-motor 18.

The several servo-motors, the mechanism of which will be described subsequently, and of which there are seven, perform the following functions:—

The function of the servo-motor 19 is to 90 open and close the valve placing the cell in communication with the ozonizer.

The function of the servo-motor 20 is to open and close the valve for supplying the cell with dry air at atmospheric pressure. 95

The function of the servo-motor 21 is to open and close the valve for supplying the ozonizer with dry air.

The function of the servo-motor 22 is to open and close the valve providing for the 100 circulation of air from the cell to the ozonizer.

The function of the servo-motor 23 is to open and close the valve putting the cell into communication with the exhaust.

The function of the servo-motor 18 is by 105 means of a barometric electric contact to start and stop the motor driving the exhaust pump.

The function of the servo-motor 24 is to

switch in or out the air-circulation pump, and the commutator of the ozonizer.

All these servo-motors are electrically controlled in the desired sequence by the clock 1, to which are connected the several electrical conductors *a*, *b*, *c*, *d*, *e* and *f*, which are also connected to the electromagnets of the servo-motors as shown diagrammatically.

The control clock is shown in Figs. 2 and 3, the clock-movement itself is not included in the drawings, it may be of any suitable kind.

A distributor wheel 25 is attached to the plates 29 and driven by a spindle 27 of the clock, the spindle 26 of the said wheel rotating at a constant but adjustable speed through the gearing of different speed drums. A pendulum 26, the length of which can be adjusted, insures the desired speed of rotation through the lever escapement, a brake with pulley 32 and weight 33 prevents by reaction the distributor wheel from turning backwards at each swing of the pendulum.

This metal distributor wheel is pierced equidistantly with holes 30 (Fig. 3) in ten rows. Each row comprises a certain number of holes (60 in the example given). The distance between two adjacent holes thus corresponds to a time interval equal to 1/60th of the total time of rotation of the wheel. Metal pins 30' with platinum tips are lodged in corresponding holes. The rotation of the wheel 25 brings the pins 30' successively into contact with flexible contacts 31 of beaten silver; these contacts carried on an insulating support have at their other ends a binding screw to which is attached the electric wire from the corresponding electromagnet controlling the order. The return conductor leads to a set of accumulators, then to the body of the distributor wheel 25 in such way that when a pin touches a contact the circuit is closed and the current will traverse the corresponding electromagnet.

It will be understood that the rotation of the wheel brings the pins thereon successively into contact with the contacts, thus starting up the servo-motors, and operating at the desired times the valves, pumps, multiple apparatus, etc.

The cycle can therefore be regulated, firstly by the speed of rotation of the wheel 25, secondly by the different positions of the pins 30', thirdly by the various connections of the contacts to the different electromagnets of the servo-motors.

The servo-motor shown in Figs. 4, 5 and 6 relates to the electro-pneumatic valves. It comprises a mechanism corresponding to what is called a "note" in the known so-called "Pleyela" apparatus, as well as two electromagnets, one for opening, the other for closing subjacent metal valves.

The so-called "note" of the Pleyela is shown at 34 and consists of the "note" proper 35 and the bellows 36. The metal air valve com-

prises a double copper cylinder 37, the smaller of which has an opening 38 and the larger an opening 39. Air can circulate from 38 to 39 through the passage 40 and the holes 41 in the smaller cylinder, then through the interior of the larger cylinder, provided that the sharp edged opening 42 of the passage 40 is not blocked by the piston 43 which slides inside the smaller cylinder and is connected to the rod 42'. A spring 43' insures the blocking up. By this means there is no communication possible between 38 and 39.

It will be understood that when current traverses the electromagnet 44, the tongue 45 attached to the armature which is attracted by the magnetization of the core of the electromagnet, opens the hole in the small pipe 45' of the "note". As there is always a vacuum at 46 inside the "note", a vacuum which is propagated by transfusion into the small pipes 45', atmospheric air rushes into 47, raises the small cylinder 48 integral with the double-shouldered valve 49, whereby this valve is constrained to leave its seat 50. As soon as the valve 50 quits its seat, its second shoulder blocks the communication with the outer air. The vacuum is then propagated through this small chamber into the bellows which then closes. In closing the member 51 acts as a lever about the pivot 52, and the outer end operates the piston rod of the obturator by opening it until held by the pawl 53.

The function of the electromagnet 44' is to release the piston of the obturator.

The starting and stopping of the exhaust pump (not shown) is effected independently of the normal course of the process by a mercury contact device. A mercury manometer, attached to the vacuum reservoir shifts a float 105 provided with a contact which comes into contact with two other adjustable contacts corresponding to fixed heights of the mercury. The first upper contact corresponds to the starting of the exhaust pump. The second bottom contact corresponds to the stopping of the exhaust pump, (shown diagrammatically at 18, Fig. 1).

In the same way when at the second time interval following the closing of the valve 20, vacuum is set up in the cell, the closing of the valve 23 is similarly effected by a mercury contact 10' (Fig. 1) the height of which can be adjusted, a small mercury manometer being connected to the cell. In this way the emptying of the air from the cell stops when the desired degree of exhaustion has been attained inside the cell.

The operation takes place in the following manner:—The wood to be seasoned having been placed in the cell, the pieces being kept apart by chocks, the cell is closed air-tight. The distributor wheel is started up, after the exhaust pump which supplies the whole plant has been started by hand for this first

130

time only, and which subsequently will only operate automatically in response to an electric contact, as above stated.

As soon as the first pin touches the first contact the valves 20 and 23 open. When the second pin touches the second contact, the valve 20 closes and so forth.

The various apparatus required for the plant will not be described, since in this first alternative these apparatus are known: they comprise the exhaust pumps, the ozonizer, the source of dry air, the electric generators as well as the current electromagnetic devices.

In large plants, where the cell will attain large size, the fact that it is subjected to external pressure might lead to certain inconveniences; moreover the working apparatus would also be of considerable size. These inconveniences can be obviated by substituting for the above-mentioned cycle another which will now be described. In this second alternative, the work is done a little above atmospheric pressure; the exhausts corresponding then to decreases of pressure below the normal working pressure, which are naturally very slight, since 1/20th atmosphere is sufficient for the decrease of pressure.

The cycle is as follows:—

	Seconds.
30 1st. Decrease of pressure below the initial working pressure (21/20th of atmospheric pressure)	20
2nd. Renewing the air at atmospheric pressure	100
35 3rd. Ozonization of the air at atmospheric pressure	60
4th. Restoration of the working pressure by re-admission of compressed air into the cell (21/20ths of atmospheric pressure)	120
40 5th. Standing	300
Total of cycle	600

45 As will be seen, the total time is the same, but the partial times have changed; for that matter these times are only given by way of example, and, according to the kind and condition of the wood to be treated, they may naturally vary without in any way departing from the principle of the apparatus as aforesaid; it is sufficient to shift the control contacts on the distributor clock.

55 The plant for putting into operation the cycle just mentioned is shown diagrammatically in Fig. 7, in which B is the cell containing the wood to be treated, it is connected on the one side with a blower V and on the other with a container R in which there is a pressure produced by a pump P. The apparatus for producing ozone is shown at O, and is connected on one side with a drying device D, which in turn is connected to a small compressor C, and on the other side to a gas holder G of suitable capacity, the bell of the

said gasholder being connected to the cell B. Suitable valves which are governed as has been described for those in the first alternative, control the whole plant and insure the complete automatic operation of the process.

70 The operation is as follows:—Besides the governing of the valves, the rise of the gasholder owing to the pressure of the ozonized air within it, or the fall of the gasholder owing to the expulsion of the ozonized air from the gasholder into the cell determines between two suitably fixed levels with electric contacts the starting up or the stopping of the small compressor C and of the ozonizer O, 80 simultaneously. The starting up or stopping of the compressor P is similarly controlled by known means, and outside the cycle, between two pressure limits. It is to be understood that the capacities of the gasholder and pressure container should be large enough to permit of obtaining rapidly and respectively within the time desired the fixed content of ozone in the air in the cell and the changes of 85 pressure in the cell B.

90 It may be assumed that the work is done at Paris for example under a working pressure equal to 800 millimetres of mercury, which with the assumed pressure difference of 1/20th of this pressure means 760 millimetres for 95 the working at so-called decrease of pressure. The four valves a, b, c and d are assumed to be closed, the first belongs to the blower pipe, the second puts the cell into communication with the outer air, the third is placed in the pipe which connects the gasholder with the cell, and the last in the pipe which connects the pressure container R with the cell. The pressure in the plant is 800 millimetres.

100 The closing of the four valves corresponds to the interval of time called "Standing"; the above described apparatus will have in order to respond to the new cycle the changes necessary for controlling the plant as follows:—

110 1st. The valve b opens and the assumed initial pressure of 800 millimetres falls to 760 millimetres, the outside atmospheric pressure.

115 2nd. The valve a opens, the blower V starts up, and the air is renewed in the cell at the normal pressure of 760 millimetres.

120 3rd. The valve a closes, the blower stops and the valve c opens, the ozonization takes place at the pressure of 760 millimetres.

125 4th. The valves c and b close and the valve d opens the pressure of 800 millimetres is slowly restored.

5th. The valve d closes, and all valves are therefore closed, standing at a working pressure of 800 millimetres.

130 It will be noticed that the ozonization takes place at a pressure relatively below the 800 millimetres working pressure, the only difference from the cycle first stated is that

the air is renewed after the pressure drop and at the low pressure, viz, 760 millimetres referred to the working pressure, which of course is of no importance.

- 5 This method of working as previously stated presents considerable advantage for large plants, for not only does it allow of the economic construction of large cells of cylindrical shape with pressure inside, but 10 further it requires only apparatus of relatively small size.

The apparatus for producing the ozone will be worked without stopping owing to the gasholder provided, the air being taken 15 from the atmosphere instead of from the cell.

Claims—

1. Apparatus for seasoning wood and the like comprising a container, an ozone generator in communication therewith, an air 20 dryer in communication with said container and with said ozone generator, exhaust means leading from said container, means for varying the pressure in said container, means for maintaining a circulation of air in said apparatus, valves for controlling said commun- 25

cations, and means for automatically actuating said valves independently of one another and for maintaining them in their open and closed positions for predetermined periods.

2. Apparatus for seasoning wood and the like comprising a container, an ozone generator in communication therewith, an air drier in communication with said container and with said ozone generator, exhaust means 30 leading from said container, means for varying the pressure in said container, means for maintaining a circulation of air in said apparatus, valves for controlling said communications, and means for automatically actuating said valves independently of one another and for maintaining them in their open and closed positions for predetermined periods, said last named means comprising clock mechanism, a control drum operated thereby 35 and having a plurality of contacts, and electromagnetic means for operating said valves and controlled by said contacts.

In testimony whereof I affix my signature.
GUSTAVE LYON.
